UNITED STATES PATENT OFFICE.

WILLIAM H. CHASE, OF HOPEDALE, MASSACHUSETTS, ASSIGNOR, BY MESNE ASSIGNMENTS, TO DRAPEE CORPORATION, OF HOPEDALE, MASSACHUSETTS, A CORPORATION OF MAINE.

FILLING-CATCHER FOR LOOMS.

1,253,148.

Specification of Letters Patent

Patented Jan. 8, 1918.

Application filed November 7, 1916. Serial No. 130,064.

To all whom it may concern:

Be it known that I, WILLIAM H. CHASE, a citizen of the United States, residing at Hopedale, county of Worcester, State of Massachusetts, have invented an Improvement in Filling-Catchers for Looms, of which the following description, in connection with the accompanying drawing, is a specification, like characters on the drawing 10 representing like parts.

This invention relates to looms wherein during the operation of the loom a spent filling carrier is ejected from the shuttle. In such cases the spent filling carrier is usually left with a small bunch of filling thereon and this filling trails back through the eye of the shuttle to a point where it is broken or severed by instrumentalities usually connected to the loom. When as in the 20 case of the automatic filling replenishing loom a fresh filling carrier is transferred into the shuttle it is important that the trailing filling from the ejected filling carrier shall be cleared from the shuttle. 25 Otherwise it may be entangled with the fresh filling and woven into the cloth.

The object of this invention is to provide a simple and efficient means for insuring that the trailing end of the filling extending from the ejected filling carrier through the shuttle eye shall be cleared from the shuttle eye as the shuttle starts on its pick to the opposite side of the loom.

This object and the features of the invention will more fully appear from the accompanying description and drawings and will be particularly pointed out in the claims.

The drawings illustrate so much of a well known type of automatic filling replenishing loom as is necessary to a disclosure of the invention with a preferred form of the invention embodied therein.

In the drawings
45. Figure 1 is a front elevation of a portion of the magazine end of an automatic filling replenishing loom of the well known Northrop type showing a preferred form of invention embodied therein and with the spent filling carrier just ejected from the shuttle;

Fig. 2 is a view in vertical transverse cross section taken on the line 2—2 of Fig. 1;

Fig. 3 is a view in perspective of the wire

filling catcher which is added to the loom in the preferred embodiment of the invention.

This invention relates only to the control of the trailing end of filling from a spent filling carrier after it is discharged from the shuttle and so the particular construction or type of loom in which it is embodied is immaterial to the scope of the invention. But the invention is of peculiar value in connection with an automatic filling replenishing loom wherein upon the substantial exhaustion of the filling a fresh filling carrier from a magazine or hopper is automatically transferred into the shuttle on 70 the lay and simultaneously the spent filling carrier is ejected therefrom and falls into a can placed beneath the loom.

The drawings accordingly illustrate a portion of the well known Northrop automatic filling replenishing loom wherein a hopper or magazine 1 is supported from the breast beam 2 at one end of the lay and contains a supply of fresh filling carriers 3. When the filling in the running shuttle becomes substantially exhausted and the shuttle 4 is boxed at the magazine end of the lay through automatic mechanism well known to those familiar with this art a transerrer 5 is operated to transfer a fresh filling carrier 3 from the hopper into the shuttle 4 therebeneath and simultaneously to force out or eject the spent filling carrier 6. For this purpose the shuttle is open at the top and bottom. As the spent filling carrier passes 90 out from the bottom of the shuttle it falls against a directing apron 7 attached to the lay and by which it is directed into a can placed beneath the loom.

In order that the change of filling carriers may take place without leaving any imperfection in the cloth a few picks of filling remain upon the ejected filling carrier usually in the form of a small bunch 8 and the spent filling end 9 trails from the bunch 8 back 100 through the eye 10 of the shuttle. It also extends a considerable distance from the eye of the shuttle back toward the fell of the cloth depending upon the point at which it is cut or broken. This end must be cleared 105 from the shuttle eye or it will become entangled with the filling of the fresh filling carrier and produce trouble and even in some cases be woven into the cloth.

In order to insure the clearing of the trail- 1

ing end of the spent filling from the shuttle this invention provides means projecting adjacent the path of the filling trailing from the ejected filling carrier through the shuttle eye which means extends between the trailing filling and the opposite side of the loom. In the specific construction illustrated this means comprises a member 11 of wire shown separately in Fig. 3 and attached to the lay so that its hooked end 12 projects downwardly and rearwardly adjacent the trailing end 9 of the filling, and it will be noted that this end 12 is located to the left of the filling 9 or between the filling and the opposite side of the loom. This wire member 11 is provided with an eye 13 and it may be placed in position with its long horizontal portion abutting the underside of the bottom plate 14 of the shuttle box and the eye 13 may be placed over and secured in position by the bolt 15 by which the right hand end of the deflecting apron 7 is secured to the lay. This affords a simple and efficient means for holding the wire member 11 in the required position.

It will be apparent that the construction of the device and the particular means by which it is supported are not of the essence of the invention in its broader aspects so long as it projects in the required relation to the trailing filling end.

The operation of the device will now be apparent. When the spent filling carrier 6 is ejected from the shuttle the filling 9 trailing therefrom will extend down adjacent the hook shaped end 12 and as the shuttle starts on the reverse pick the filling will reeve about the part 12 and be retarded thereby so as to cause the withdrawal of the spent filling end from the shuttle eye. The action is a quick one because the parts are in motion and it is aided by the fall of the spent filling carrier into the can. The filling end is therefore given a quick turn about the hooked end 12 and the retarding action is so aided by the momentum of parts that

the spent filling end is readily withdrawn through the shuttle eye.

Having fully described my invention, what I claim as new and desire to secure by Letters Patent is:

1. A loom comprising means for ejecting a spent filling carrier from the shuttle when at the end of its pick and means secured to the lay and projecting adjacent the path of the filling trailing from the ejected filling carrier through the shuttle eye and extending between the said trailing filling and the opposite side of the loom whereby as the shuttle starts on the reverse pick the trailing filling reeves about and is retarded by said means and is thus drawn out from the shuttle.

2. A loom comprising means for ejecting a spent filling carrier from the shuttle when at the end of its pick, a hooked shaped member secured to the lay and having its hooked end projecting adjacent the path of the filling trailing from the ejected filling carrier through the shuttle eye and located between the said trailing filling and the opposite side of the loom whereby as the shuttle starts on the reverse pick the trailing filling is caught and retarded by the hooked end and thus drawn out from the shuttle.

3. A loom comprising means for ejecting a spent filling carrier from the shuttle when at the end of its pick, a device secured to the lay and projecting therefrom adjacent the path of the filling trailing from the ejected filling carrier through the shuttle eye and located between the said trailing filling and the opposite side of the loom whereby as the shuttle starts on the reverse pick the trailing filling is caught and retarded by said device and thus drawn out from the shuttle.

In testimony whereof, I have signed my name to this specification.

WILLIAM H. CHASE.
